SNOW SLED BODY

Allan W. Lund, 2641 118th Ave. NW,
Minneapolis, Minn. 55433

Filed Dec. 14, 1970, Ser. No. 26,485

Term of patent 14 years

Int. Cl. D12—13

U.S. Cl. D14—24

FIG. 1

FIG. 2

FIG. 3

FIG. 1 is a top plan view of a snow sled body embodying applicant's invention;

FIG. 2 is a side elevation thereof;

FIG. 3 is a front elevation thereof; and

FIG. 4 is a rear elevation thereof.

The elements shown in broken lines are included for illustrative purposes only.

I claim:

The ornamental design for a snow sled body, substantially as shown and described.
